(57) **CLAIM**

The ornamental design for a slider for slide fastener, as shown and described.

DESCRIPTION

FIG. 1 is a perspective view of the front, top and right side of a slider for slide fastener, showing our new design; FIG. 2 is a front view thereof;

FIG. 3 is a rear view thereof;

FIG. 4 is a right side view thereof, the left side view being essentially mirror image thereof;

FIG. 5 is a top plan view thereof; and,

FIG. 6 is a bottom view thereof.

The broken lines shown are included for the purpose of illustrating the unclaimed portions of a slider for slide fastener and form no part of the claimed design. The dot-dash lines define the bounds of the claimed design and form no part thereof.
